UNITED STATES PATENT OFFICE

163,111

COMBINATION FOOD CART AND TABLE

Allen K. Gibbon, Kansas City, Mo.

Application March 14, 1949, Serial No. 1,388

Term of patent 7 years

(Cl. D33—14)

To all whom it may concern:

Be it known that I, Allen K. Gibbon, a citizen of the United States, residing at Kansas City, in the county of Jackson, and State of Missouri, have invented a new, original, and ornamental Design for a Combination Food Cart and Table, of which the following is a specification, reference being had to the accompanying drawing, forming a part thereof.

Fig. 1 is a side elevational view of a combination food cart and table, showing my new design.

Fig. 2 is a rear elevational view thereof.

Fig. 3 is a plan view of the device shown in Fig. 1, but with the sides thereof in a lowered position and the top cover removed;

Fig. 4 is a front elevational view of the combi-

nation food cart and table in the position illustrated in Fig 3.

I claim:

The ornamental design for a combination food cart and table, as shown.

ALLEN K. GIBBON.
